UNITED STATES PATENT OFFICE.

CALVIN JACKSON, OF READING, PENNSYLVANIA.

DESIGN FOR A TOOL-HOLDER FOR METAL-WORKING LATHES.

SPECIFICATION forming part of Design No. 31,863, dated November 21, 1899.

Application filed September 18, 1899. Serial No. 730,941. Term of patent 14 years.

To all whom it may concern:

Be it known that I, CALVIN JACKSON, a citizen of the United States of America, and a resident of Reading, in the county of Berks and State of Pennsylvania, have invented and produced a certain new and original Design for a Tool-Holder for Metal-Working Lathes, of which the following is a specification.

Figure 1 is a side elevation; Fig. 2, a top view, and Figs. 3 and 4 end views.

As shown in the drawings, my design consists, essentially, of a rectangular shank portion *a* and an eccentrically-located cylindrical head *b*. The rectangular portion *a* is

provided with a round opening or bore *c*, arranged concentric with and joining a conical recess *d* in the cylindrical head *b*. The latter is filleted into the rectangular shank *a*, as indicated at *e* and *f*. 20

What I claim is—

The design for a tool-holder for metal-working lathes substantially as shown and described.

Signed by me at Reading, Pennsylvania, 25 this 4th day of September, 1899.

CALVIN JACKSON.

Witnesses:

W. G. STEWART,

ADAM L. OTTERBEIN.
